UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

RADIOTELEPHONY.

No Drawing. Application filed August 29, 1921. Serial No. 496,650.

(GRANTED UNDER THE PROVISIONS OF THE ACT OF MARCH 3, 1921, 41 STAT. L. 1313.)

To all whom it may concern:

Be it known that I, MARIUS LATOUR, a citizen of France, and resident of Paris, France, have invented certain new and useful Improvements in Radiotelephony (for which I have filed an application in France, February 14, 1917, resulting in French Patent No. 493,924, granted May 16, 1919), of which the following is a specification.

It has already been demonstrated that the use of a local continuous current wave source in a wireless telegraph receiving station in accordance with the so-called "heterodyne" principle, results in a marked amplification of received signals.

Heretofore, such local source was used only for the receiving of telegraphic signals.

In accordance with the present invention, the use of a local continuous current wave generator is extended to the reception in wireless telephony.

By establishing a sufficiently low or sufficiently high difference between the frequencies of the received and locally generated oscillations, the arrangement will be adjusted so that the permanent sound thus obtained will not interfere with the intelligibility of the sounds corresponding with the speech.

This method of receiving enables one to make sure of the functioning of the corresponding station.

Having described my invention, what I claim is:

1. The method of receiving telephonic signals transmitted by high frequency oscilla-

tions which consists in superimposing locally generated high frequency oscillations on the received oscillations and adjusting the difference of the locally generated frequency and the signal frequency within the limits of audibility so that the beat note does not interfere with the speech.

2. The method of receiving telephonic signals transmitted by high frequency oscillations through space which consists in superimposing locally generated continuous high frequency oscillations on the received oscillations and adjusting the beat frequency to give an audible tone considerably higher or considerably lower than the normal speech frequencies.

3. The combination with means responsive to modulated carrier waves of means associated with said responsive means for producing audible beat notes from said carrier waves that do not interfere with the modulated frequencies.

4. The combination of means responsive to carrier waves modulated by audible frequencies, of means associated with the said responsive means for producing audible beat notes from said carrier waves that do not interfere with the modulated audible frequencies.

5. The combination with means responsive to carrier waves modulated by speech frequencies of means associated with said responsive means for producing audible beat notes from said carrier waves that do not interfere with the speech frequencies.

MARIUS LATOUR.
